UNITED STATES PATENT OFFICE

WILLIAM S. PRITCHARD, OF DETROIT, MICHIGAN, ASSIGNOR TO MOTOR PRODUCTS CORPORATION, OF DETROIT, MICHIGAN, A CORPORATION OF NEW YORK

WINDOW LIFTER

Application filed February 13, 1928. Serial No. 254,082.

This invention relates to window controlling devices and has particular application to control devices for the sliding windows of automobiles and other vehicles.

One of the primary objects of the present invention is to provide a device of the above character distinguished by its simplicity of construction and operation, which not only enhances its value both mechanically and commercially, but provides a design of a strong and durable nature and one that may be economically manufactured.

A further object of the invention is to provide a mechanism wherein the usual racks and gears for swinging the lifter arm and their accompanying inefficiencies are eliminated and one that affords a relatively greater leverage so that only a minimum amount of effort is required to operate the window.

Further objects of the invention reside in the peculiar construction of the lifter mechanism which will be made more apparent as this description proceeds, especially when considered in connection with the accompanying drawings wherein,

Figure 1 is an inside elevation of a vehicle door with the lining removed and showing a window control mechanism embodying my invention;

Figure 2 is a rear elevational view of the lifter actuating mechanism;

Figure 3 is a sectional view taken on the plane indicated by the line 3—3 of Figure 2;

In the present instance the invention is shown as applied to the door 10 of a motor vehicle having in its upper portion the opening 11 and in its lower portion the chamber 12 for receiving the window 13 when lowered from a position closing the opening 11. Secured to the door in any suitable manner and preferably although not necessarily, extending across the same is the lock board 14. Secured to the lock board intermediate the ends thereof is the actuating mechanism 15 for adjusting the glass panel or window 13. This actuating mechanism includes two annular spaced sheet metal members 16 and 17 secured together at the periphery thereof in any suitable manner forming an annular housing 18.

Rotatably mounted within the housing 18 and having a diameter substantially equal to the interior diameter of the housing is an actuating member 19. As shown, the member 19 is formed from sheet metal and is provided with a series of corrugations, the distance between the crests of the corrugations being substantially equal to the width of the housing 18 so that the member 19 not only contacts with the end walls of the housing throughout its periphery, but also contacts with the opposite inner side walls of the members 16 and 17 of the housing and accordingly lateral or endwise movement of the actuating member relative to the housing is prevented. The corrugations formed in the member 19 are so designed that they form a continuous spiral passage 20 extending from a point adjacent the center of the member 19 to a point adjacent the periphery thereof, as clearly illustrated in the drawing. Journalized within aligned centrally arranged apertures 21 and 22 formed in the members 16 and 17 respectively is an operating shaft 23 having an enlarged portion 24 intermediate the ends thereof disposed within the housing 18. The inner annular shoulder 25 of the enlarged portion preferably has a bearing engagement with the inner wall of the member 17 and the outer shoulder 26 is secured to the substantially flat portion 27 of the member 19 and maintains the same in contacting relation with the inner wall of the member 16. The shaft 23 is provided with the usual squared portion 28 upon which the customary operating handle is adapted to be secured.

For connecting the actuating mechanism to the glass, I provide the control arm 29 having a roller 30 upon the outer end thereof arranged to engage a laterally opened channel shaped strip attached to the bottom edge of the glass panel and fashioned to retain the roller 30 therein. The inner or opposite end of the control arm is pivotally connected to a lever 31 by means of the pin 32. The opposite end of lever 31 is fulcrumed upon the housing 18 by means of the pin 33. Secured respectively to the arm 29 and lever 31 at a predetermined distance from the pivotal connection 32 are the laterally project-

ing pins 34 and 35. As shown these pins project through arcuate slots 36 and 37 formed in the member 16 of the housing and project within the spiral passage 20. The 5 extent of curvature of the slots being calibrated to coincide with the path of travel of the pins 34 and 35 about the fulcrum 33 from one extreme position of the arm 29 and lever 31 to the other extreme position.

10 With the foregoing arrangement, it will be noted that when the parts are in the position illustrated by the full lines in Figure 1 the pin 34 will be positioned adjacent the inner end of the passage 20, while the pin 35 15 upon the lever 31 will assume a position slightly forwardly of the pin 34 so that when the member 19 is caused to rotate the pins will be compelled to travel in the path defined by the arcuate slots 36 and 37 and in 20 so doing swing the arm 29 and lever 31 about the fulcrum 33 until these parts assume the dotted line position illustrated in Figure 1. In this latter position of the parts, the pin 35 is positioned adjacent the outer end of the 25 circuitous passage 20, and the pin 34 is positioned to the rear of this pin.

Thus from the foregoing, it will be apparent that owing to the peculiar construction of the operating mechanism proper an 30 unusual amount of leverage is afforded and accordingly comparatively little effort is required to raise or lower the window. If desired, a suitable coil spring (not shown) may be utilized to counterbalance the weight of 35 the window, and thus further minimize the effort required to operate the window. The herein described construction is also inherently self-locking so that the window may be retained in any of its adjusted positions.

40 An arrangement of the above character offers the possibility of eliminating complicated and inefficient operating means for the vertically movable glass panel and renders possible the production of a commercially 45 satisfactory device that is simple in construction, efficient and positive in operation and one that is relatively inexpensive to manufacture.

What I claim as my invention is:

50 1. The combination with a frame and a closure slidable in said frame, of actuating means for said closure including an annular housing carried by said frame, an annular member rotatably mounted within said housing having a spirally arranged passage in one face thereof, and a control arm having one end connected to said closure and having a lateral projection intermediate the ends projecting through an arcuate slot 55 formed in one wall of said housing and engageable with the passage aforesaid.

60 2. The combination with a frame and a closure slidable in said frame, of actuating means for said closure including a housing 65 secured to the said frame, a member rotatably

mounted within said housing having a circuitous passage in one face thereof, and a control arm having a portion connected to said closure and having another portion projecting through an arcuate slot formed in one 70 wall of said housing and engageable with the passage aforesaid, said arcuate slot being calibrated to coincide with the path defined by the projection during the movement of the lever.

75 3. In a device of the class described, the combination with a frame and a closure slidable in said frame, of means providing a spiral guide, a pair of levers having their adjacent ends pivotally connected and having their opposite ends connected respectively to a fixed support and to said closure, means carried by said levers engaging respectively in said guide, and means for rotating said guide, as and for the purpose 80 set forth.

85 4. In a device of the class described, the combination with a frame and a closure slidable in said frame, of a member having a spiral groove in one face thereof, a pair of pivotally connected levers, the free end of one lever being pivoted to a fixed support, the free end of the other lever being connected to said closure, means upon said levers engaging respectively in said groove, and means for rotating said member, as and for the purpose 90 set forth.

95 5. The combination with a frame and a closure slidable in said frame, of actuating means for said closure including a housing 100 secured to the said frame, a corrugated member rotatably mounted within said housing, said corrugations arranged to cooperate with one wall of said housing to form a closed spirally arranged passage, and an operable 105 connection between said recess and closure.

6. The combination with a frame and a closure slidable in said frame, of actuating means for said closure including a housing 110 secured to said frame, a control arm having one end connected to said closure, a lever having one end fulcrumed upon a fixed part and the opposite end pivotally connected to said control arm, and means disposed within said housing connected to said control arm 115 and lever intermediate the ends thereof for actuating the same.

7. The combination with a frame and a closure slidable in said frame, of actuating means for said closure including a housing 120 secured to said frame, a control arm connected to said closure, a lever pivotally connected to said control arm and fulcrumed upon said housing, said lever and control arm having lateral projections intermediate 125 the ends thereof arranged to project through slots formed in one wall of said housing, and means arranged within said housing operatively engaging the said projections for actuating said control arm and lever.

8. The combination with a frame and a closure slidable in said frame, of actuating means for said closure including a housing secured to said frame, a control arm connected to said closure, a lever pivotally connected to said control arm and fulcrumed upon said housing, said lever and control arm having lateral projections intermediate the ends thereof projecting through arcuate slots formed in said housing, and a rotatable member disposed within said housing having a spirally arranged groove formed in one face thereof for receiving the projections aforesaid.

15 9. The combination with a frame and a closure slidable in said frame, of actuating means for said closure including a member rotatably carried by the frame and having a spirally arranged passage formed in one face thereof, a control arm connected to said closure, a lever pivotally connected to said control arm and fulcrumed to a fixed part, and means carried by the control arm and lever engageable in the passage formed in said member for swinging the control arm and lever about the said fulcrum upon rotation of the said member.

10. The combination with a frame and a closure slidable in said frame, of actuating means for said closure including a stationary part, a member rotatably mounted upon said stationary part having a spirally arranged passage therein, a control arm connected to said closure, a lever pivotally connected to said control arm and fulcrumed upon a support, means carried by the control arm and lever engageable in said spirally arranged passage for swinging the said control arm and lever upon rotation of the member, and means engageable with the last-mentioned means for accurately guiding said control arm and lever along predetermined paths.

11. The combination with a frame and a closure slidable in said frame, of actuating means for said closure including a stationary part, a member rotatably mounted upon said stationary part having a spirally arranged passage therein, a control arm connected to said closure, a lever pivotally connected to said arm and fulcrumed upon a support, and lateral projections carried by said control arm and lever extending through arcuate slots formed in said stationary part and engageable with the passage aforesaid, the paths defined by said slots being calibrated to coincide with the paths defined by said projections during the swinging movement of the control arm and lever.

12. In a device of the class described, the combination with a frame and a closure slidable in said frame, of a rotatable member having a spiral groove formed therein, a pair of pivotally connected levers, the free end of one lever being pivoted to a fixed support, the free end of the other lever being connected

to said closure, means on each of said levers engaging in said groove at one side of the axis of rotation of said member and means for rotating said member.

In testimony whereof I affix my signature. 70
WILLIAM S. PRITCHARD.
